Cordley & Hayes, New York, N. Y., a corpora-
tion of New York

Application September 15, 1933, Serial No. 689,586

3 Claims. (Cl. 62—143)

This invention relates to improvements in water coolers which support inverted bottles, particularly such coolers as have a compartment for receiving food stuffs at one side of a well which contains water fed from the inverted bottle. It is generally desirable that such coolers be as compact as is possible, consistent with the volume of water and food stuffs to be cooled, and also that the inverted bottle be centrally located with respect to the main body of the cooler so that the bottle, which may be heavy, will not tend to upset the cooler and so that the construction will present a balanced and attractive appearance. Furthermore, it is desirable that the food compartment be closed off from the water compartment so that odors from the foods will not spoil the taste of the water. To provide adequate space for a suitable food or bottle cooling compartment the water receptacle must be offset to one side of the center of the cabinet. When inverted bottles are placed on such a cooler, on account of the limited clearances, required by practical considerations, between the mouth of the bottle and the nearest portion of the offset water receptacle, it frequently happens that the neck of the bottle strikes the wall of the receptacle with the result that either the bottle or wall is chipped, damaged or broken. At the same time, the bottle is tipped while it is being put in place, so that water is apt to flow out of the bottle and splash over the top of the wall of the well, with the result that it lodges on the top plate where it may rust parts of the construction or leak into the food compartment.

An object of the present invention is to provide a construction which meets the various outlined requirements in a superior manner and at the same time avoids the disadvantages enumerated, while being simple and inexpensive to manufacture. Other objects and advantages will become apparent as the following detailed description of one form of construction in accordance with the invention proceeds, reference being had to the accompanying drawing, where-

in:

Fig. 1 is a front elevation, partly in section and partly broken away, of the upper portion of an illustrative cooler, and

Fig. 2 is a plan view of an improved ring constituting a feature of the construction.

Referring to the drawing, there is shown at 1 the upper portion of a cabinet enclosing the construction and having a cover 2 removably carried therewith. The cover 2 has a central aperture through which the neck of an inverted bottle

3 is adapted to extend. The cabinet receives and carries a well 4 formed of enamel ware or other suitable rust proof and easily cleanable material and adapted to hold water which flows into it from the bottle. As will be understood the well 5 or water receptacle becomes filled to a level at which it serves to seal the mouth of the bottle, this being considerably below the top of the well. The well 4 is off-center with respect to the neck of the bottle in order to provide space for a compartment 5 at one side of the cabinet for receiving food stuffs, milk bottles, and so forth, which may be introduced into the compartment 5 through the door 6. The compartment 5 may be of any suitable form and construction, either 10 as a separate, enclosed chamber or as the entire free space within the cabinet. A cooling coil 7 surrounds the well 4 to cool the water therein. This coil, it will be understood, is in communication with any convenient form of refrigerating unit, not shown. If desired, ice might be used in place of the cooling coil. Separate cooling means may be provided for compartment 5, if desired. The cooled water may be withdrawn through a faucet 8 in the usual manner. 20 A top plate 9 may be detachably secured to the top edges of the wall of the well in any convenient manner and be arranged to prevent circulation of the air from the space around the cooling coils and from within or around the compartment 5 30 into the space above the water in the well. By supporting the bottle through a removable cover above the partition 9, the well is readily accessible for cleaning, and the construction may be easily and simply assembled.

The inverted bottle 3 is supported on the cover 2 through portion 10 of a unitary ring or gasket 11 formed of rubber or other suitable cushioning material, the portion 10 being seated upon a substantially flat portion 12 of the cover, which portion surrounds the central opening. The ring 11 has a generally downwardly extending, relatively thin portion 13 which merges at its upper end with the inner wall of portion 10 and is adapted to engage the edge of the central opening through portion 12 to position the ring on the cover. The portion 10 may thus be considered as a thick flange on portion 13. The lower end of portion 13 of the ring is of reduced diameter so as to more closely surround the neck of the bottle, lying 50 between the neck and the wall and extending within the well to a sufficient distance below the top of the wall of the well to prevent water from splashing over the top of the well onto the top plate 9, yet terminating slightly above the 55

surface of the water. Preferably, as stated, the lower end of portion 13 is of considerably smaller diameter than the portion 10, or in other words, the portion 13 flares outwardly and upwardly to 5 form a sort of funnel. The lower end of portion 13 may advantageously extend parallel to the neck of the bottle for a substantial distance. Yielding means are thus provided for guiding the neck of the bottle when it is positioned or re- 10 moved and a funnel is formed to prevent undesirable splashing. Suitable air vent grooves 14 may be provided on the under surface of the flange portion 10 and these may be extended vertically along the upper end of the portion 13. It 15 will be understood that provisions for venting may be made in other ways, if desired. The grooves might, for example, be placed in the upper surface of the ring which supports the bottle, or venting may simply take place through the cover. 20 I have found that through a construction of present character, the various requirements outlined are satisfied in a most effective manner. Breakage either of the well or bottle, and splashing 25 of the water out of the well, while the bottle is being put in place, are substantially avoided by the simple, unitary cushioning device which is readily assembled with the other parts of the construction and retained in place without the need for extraneous retaining means. 30 The terms and expressions which have been employed are used as terms of description and not of limitation, and there is no intention, in the use of such terms and expressions, of excluding 35 any equivalents of the features shown and described, or portions thereof, but it is recognized that various modifications are possible within the scope of the invention claimed.

I claim:

40 1. In a cooler construction adapted to support an inverted bottle, a well, a housing surrounding

the well, said well being off center with respect to the housing, a food compartment at one side of the well, a plate secured to the top of the well and extending across the balance of the housing, a removable cover for the housing above said plate, said cover having a central aperture through which the neck of an inverted bottle is adapted to extend, and generally annular cushioning means including a flange portion for seating said bottle on said cover and a portion extending downwardly and lying adjacent the edge of said aperture at its upper end and having its lower end below the top of the well adjacent a portion of the wall thereof. 10

2. In a cooler construction including a cabinet, 15 a well disposed off center with relation to the cabinet, a compartment for food-stuffs at one side of the well, a removable top for the cooler having an aperture centrally located with respect to the construction and through which the neck of 20 an inverted bottle is adapted to extend, and unitary, funnel-shaped, cushioning means for supporting an inverted bottle on the top by engagement with the bottle at points well removed from the neck thereof, said means having an apron 25 adapted to prevent the neck of the bottle from striking the well and to prevent splashing of water out of the well while the bottle is being placed on the cooler.

3. In a device of the class described including 30 a well, a funnel-shaped cushioning member mounted at a point above the well and having a portion at its top adapted to support an inverted bottle by engagement of the top thereof at points 35 well removed from the neck and having an open-ended downwardly extending apron portion extending an appreciable distance along but spaced from and approaching the neck of the bottle.
